Fig. 2.

UNITED STATES PATENT OFFICE.

AMOS SHEPARD, OF PLANTSVILLE, CONNECTICUT.

DESIGN FOR A WRENCH MEMBER.

SPECIFICATION forming part of Design No. 33,468, dated October 30, 1900.

Application filed October 5, 1900. Serial No. 32,191. Term of patent 14 years.

To all whom it may concern.

Be it known that I, AMOS SHEPARD, a citizen of the United States, residing at Plantsville, in the county of Hartford and State of Connecticut, have invented and produced a new and original Design for a Wrench Member, of which the following is a specification, reference being had to the accompanying drawings, forming part thereof.

Figure 1 is a side elevation of the bar member of a wrench, showing my new design. Fig. 2 is an edge view of the same. Fig. 3 is a transverse section on the line $x-x$ of Fig. 1.

As shown in the drawings, the bar member of the wrench comprises the fixed jaw or head 3, the bar-body 4, step 5, bolster 6, and handle-web 7. The fixed jaw or head is of the ordinary square form in cross-section and in side view is of the ordinary rectangular form 20 with one corner of the rectangle cut off or lacking, as shown in Fig. 1. The main portion of the body 4 of the bar is also of the ordinary form—rectangular in cross-section.

At the handle end of the bar-body is the step 25 5, that is shaped with flat sides 8, which are parallel to the broadest flat sides 9 of the wrench-bar body and are in continuation thereof. The front side of the step is straight and flat, while its rear side 10 is of a rounded 30 form, which meets the lower edge of the handle-web 7 by a short curve 11, Fig. 1. At the junction of the bar-body and handle-web on the broad sides of the said body is the bolster 6, of a straight form 12 on its back face and 35 curved and rounded on its front face 13, as shown; but the said curved and rounded front does not extend toward the head of the wrench

so far as does the step, so as to interfere with the shape before described, wherein the sides 8 of the step are straight and in continuation of the flat sides 9 of the wrench-bar body.

The contour of the handle-web in side view is clearly shown in Fig. 1, and on the middle of each broad side of the said web is a central 45 longitudinal bead 14, of semicircular form in cross-section. At the rear end of the handle-web is a button-like circular boss 15, projecting from both sides thereof. At the junction of the handle-web and bolster there are flat 50 faces 16, extending obliquely to the handle-web, which they meet at an angle at their rear ends, while their forward ends meet the straight face 12 of the back of the bolster. There is also a conical-shaped enlargement 55 17 of the beads 14 at their forward end, that merges into the straight flat oblique faces 16. On the back edge of my wrench member there is a projecting rounded bead 18, that extends forward of the handle-web in continuation of 60 one edge thereof and along the back edge of the bar-body for a portion of its length.

The various shapes blend into each other in one harmonious unitary design, all as shown.

Having described my invention, what I claim as new, and desire to secure by Letters Patent, is—

The design for a wrench member, as herein shown and described.

AMOS SHEPARD.
